[57] CLAIM

The ornamental design for a gun for determining current or power in an electrical conductor, substantially as shown and described.

DESCRIPTION

FIG. 1 is a top and right rear perspective view of a gun for determining current or power in a electrical conductor;

FIG. 2 is a right side elevational view thereof, the left side being substantially a mirror image thereto;

FIG. 3 is a top plan view thereof;

FIG. 4 is a bottom plan view thereof;

FIG. 5 is a front elevational view thereof;

FIG. 6 is a rear elevational view thereof.

*FIG. 1.**FIG. 5.**FIG. 6.*FIG. 3.

FIG. 2.

FIG. 4.
